United States Patent Office.

WILLIAM H. HAWLEY, OF UTICA, NEW YORK.

Letters Patent No. 69,992, dated October 22, 1867.

IMPROVEMENT IN GRAPPLING-IRONS.

The Schedule referred to in these Letters Patent and making part of the same.

TO ALL WHOM IT MAY CONCERN:

Be it known that I, WILLIAM H. HAWLEY, of Utica, Oneida county, New York, have invented a new and useful Improvement in Grappling-Irons for suspending ropes, elevating blocks, and the like; and I do hereby declare that the following is a full, clear, and exact description of the said invention, and of the mode of operation of the same, reference being had to the annexed drawings, in which—

Figure 1 represents a perspective view of the invention.

Figure 2 is a side view of the grapples open and closed, and

Figure 3 is a perspective view of the elevating and detaching apparatus.

A A are the arms, A¹ the joint on which they turn, B B the bars or levers, and B¹ B¹ and B² the pins of the toggle-joint; C, a hook; D, the elevating and detaching apparatus, having arms D¹ D¹ and a hook, D², and all attached to D³, the pole. E, the beam to which the grapple is attached. The arms A A are jointed at their lower end A¹, and are curved outward and then inward at their points, in such manner that said points may most readily take hold of the beam to which they are to be attached. They may be of cast malleable or wrought iron. At about the point where the arms are the farthest apart is the toggle-joint B, connecting the two arms, composed of two bars or levers B B; one end of each of which is joined to an arm; A, by a pin, B¹, and the other ends of said levers are joined to each other by the centre-pin or bolt B². Between these two ends is placed the end of the hook C, through which said pin or bolt B² also passes. This hook C extends down below the joint A¹. By drawing or pressing up the hook C the grapple is opened and closed. The elevating and detaching apparatus consists of a pole, D³, and a T-formed piece of iron, D, attached to the upper end thereof. The upper arms D¹ D¹ are curved inward and upward, as seen in figs. 1 and 3, and the lower end is formed into a hook, and turned at right angles across the pole, as is also seen in figs. 1 and 3.

The mode of operation is as follows: It is obvious that if the points of the arms A A are placed each one on opposite sides of a timber, and a weight suspended from the hook C, the toggle-joint B will draw down the parts together and cause them to adhere to the timber, the firmer the greater the suspended weight. It is also obvious that when the toggle-joint B is forced up, as it may be by pressing up C, it will cause the arms to open and release them from the timber. If the position to which the irons are to be raised is too high to be reached by hand, the lower end of the grapples may be placed in the elevating apparatus, the arms D¹ D¹ in front, and the lower end of C resting in the hook D², as seen in fig. 1, and with the pole the grapples, blocks, and ropes may be elevated to the desired point, when, by swinging the ropes to the left, the hook C will pass out of the hook D², and, the weight of the pulley-blocks and ropes being allowed to operate on the toggle-joint through the hook C, will cause the grapples to close on the timber. When the grapples are to be lowered the elevating apparatus is placed in the position it was when the grapples were raised, and the hook D², being pressed up against the curve of the hook C, presses up the toggle-joint and the grapples are released from the timber, when they may be lowered.

This form of grappling-irons is simpler, cheaper, stronger, and more easily operated than any in use hitherto.

What I claim as my invention, and desire to secure by Letters Patent, is—

1. The combination of the arms A A, toggle-joint B, and hook C, constructed and operating substantially as described and for the uses and purposes mentioned.

2. In combination with the grappling-irons the elevating and detaching apparatus, constructed and operating substantially as described.
